UNITED STATES PATENT OFFICE.

JAMES WILKINSON, OF LYNNFIELD, MASSACHUSETTS, ASSIGNOR TO GENERAL ELECTRIC COMPANY, A CORPORATION OF NEW YORK.

EMERGENCY GOVERNOR.

Application filed October 5, 1925. Serial No. 60,368.

The present invention relates to emergency governors such as are used in connection with elastic fluid turbines for example, and which function in case of overspeed of the turbine to effect shutting off of the supply of actuating fluid to the turbine.

In connection with such governors, it is desirable to provide means whereby they can be tested from time to time to determine their operative condition, and this without overspeeding the machine, and the object of my invention is to provide an improved construction and arrangement for accomplishing this result.

For a consideration of what I believe to be novel and my invention, attention is directed to the accompanying description and the claims appended thereto.

In the drawing Fig. 1 is a diagrammatic view of an elastic fluid turbine provided with an emergency governor embodying my invention; Fig. 2 is a sectional plan view of the emergency governor; Fig. 3 is a transverse sectional view taken on line 3—3, Fig. 2; Fig. 4 is a sectional view taken on line 4—4, Fig. 3; and Fig. 5 is a sectional view taken on line 5—5, Fig. 3.

Referring to the drawing, 1 indicates an elastic fluid turbine of any suitable type. 2 indicates the shaft of the turbine, 3 the conduit through which elastic fluid is supplied to the turbine and 4 a combined trip and throttle valve located in conduit 3. The combined trip and throttle valve may be of any suitable type, it being essential only that it close automatically when the turbine governor operates to trip it. In the present instance, a valve of known type is indicated, the same being held open by a latch 5. Latch 5 is connected by a rod 6 to a bell crank lever 7 pivoted on a frame 8. Connected to bell crank lever 7 is a plunger pin 9 which rests on the upper end of a pivoted trip finger 10. On plunger pin 9 is a collar 11 between which and a wall 12 is arranged a spring 13 which acts in a direction to force pin 9 downward. The pin 9 is normally held in its upward position by trip finger 10 and in this position latch 5 holds valve 4 open. The outer end of trip finger 10 extends down into proximity to shaft 2 and is adapted to be engaged by the emergency governor and turned on its pivot, thereby moving it from under

plunger pin 9. When moved from under plunger pin 9, spring 13 forces the plunger pin downward, turning bell crank 7 on its pivot and through rod 6 moving catch 5 to release the emergency valve and permit it to close.

The construction so far described is a known one used in connection with elastic fluid turbines. It is shown only by way of example and as being one arrangement in connection with which my invention may be utilized.

Shaft 2 is provided with an enlarged portion 14 at its end which portion may be formed integral with the shaft or otherwise suitably connected thereto. In portion 14 is a recess or well 15 in which is located the emergency governor plunger member 16. On the inner end of member 16 is a piston 17 which fits recess 15, the recess thus forming a cylinder in which piston 17 moves. 18 indicates a stop for piston 17. At the outer end of recess 15 is a flange 19 against which rests a guide 20 for the outer end of member 16. Guide 20 has a threaded portion 21 upon which is a nut 22. Located between nut 22 and a flange 23 on piston 17 is a compression spring 24. Spring 24 serves to bias piston 17 against stop 18 and to hold plunger member 16 against outward movement. By adjusting nut 22 on threaded portion 21 the tension of spring 24 may be adjusted. The plunger member 16 has its center of gravity to the right hand side of the axis of shaft 2 as seen in Fig. 2 so that when the shaft is rotating centrifugal force tends to move plunger member 16 outward. The compression of spring 24 is such that at normal speed of the shaft it holds plunger member 16 from movement but in case of overspeed the centrifugal force overcomes spring 24 and moves plunger member 16 outward. When this occurs the end of plunger member 16 strikes trip finger 10 to effect closing of the emergency valve.

Beneath piston 17 and surrounding stop 18 is a chamber 25 which is connected by an axially and radially extending passage 26 to a scoop 27 formed on enlarged portion 14 at one side of recess 15. Surrounding enlarged portion 14 in the plane of scoop 27 is a wall 28 having an annular groove 29 in its inner surface which groove opens directly toward enlarged portion 14. Scoop 110

27 projects into groove 29 and rotates there-
in when shaft 2 is rotating. Connected to
groove 29 are one or more supply pipes 30,
two being shown in the present instance,
5 placed 180° apart. These pipes extend tan-
gentially to groove 29 and are adapted to
discharge a liquid such as oil into groove
29. They are shown as being connected to
a suitable supply pipe 31 which may lead
10 from any suitable source of fluid pressure,—
ordinarily, the fluid used in the case of elas-
tic fluid turbines is oil,—the pipe 31 then
connecting with the pressure lubricating sys-
tem for the turbine. In pipe 31 is a valve
15 32 which is normally closed but which may
be opened by means of a hand lever 33.
Normally valve 32 is closed so that no liquid
is being supplied to groove 29. In en-
larged member 14 is an axially extending
20 port 34 which is normally covered by pis-
ton 17.

When the turbine is running under nor-
mal operating conditions, valve 32 is closed
as already stated and the emergency gov-
25 ernor rotates with the shaft in the usual
manner, scoop 27 revolving in groove 29.
In case of excess speed of the turbine, plun-
ger member 16 will fly outward to strike
trip finger 10 and effect closing of the emer-
30 gency valve in the usual and well under-
stood manner.

When it is desired to test the emergency
governor, lever 33 is depressed to open valve
32 to supply liquid to annular groove 29.
35 Scoop 27 thereupon catches liquid from
groove 29 and forces it through passage 26
to chamber 25 to build up a pressure there-
in which acts on piston 17 thereby forcing
plunger member 16 outward against the ac-
40 tion of spring 24 and effecting tripping of
the emergency governor.

Referring particularly to Fig. 3, it will
be noted that the liquid supplied to groove
29 enters it tangentially in a direction oppo-
45 site to that in which shaft 2 rotates. The
liquid enters the groove with considerable
velocity. Since the open end of the scoop
moves in a direction opposite to the direction
of flow of the liquid, the speed of the ro-
50 tation of the shaft is added to the velocity
of the liquid in forcing liquid through pas-
sage 26. With this arrangement, pressure
will be built up quickly under piston 17. By
providing two supply pipes 30 arranged
55 180° apart, liquid will be supplied continu-
ously to the scoop. In Fig. 3 of the drawing
the scoop is shown as having just passed
the lower pipe 30 and as having scooped
the liquid out of the upper portion of
60 groove 29. In the meantime, the lower por-
tion of the groove has become filled from the
upper pipe 30 and as the shaft rotates it
will scoop up this liquid. While this is
taking place lower pipe 30 will again fill
65 the upper portion of the groove as seen in

Fig. 3, so that when scoop 27 passes the
upper pipe 30 it will strike the liquid which
in the meantime has entered the upper por-
tion of the groove from the lower pipe 30.

When piston 17 and plunger member 16 70
move outward, port 34 is uncovered. The
liquid under piston 17 can thereupon flow
rapidly through the space beneath piston 17
serving to flush out any sediment which may
have collected therein. 75

As soon as the governor has operated,
valve 32 is closed. The liquid under piston
17 thereupon flows out through passage 34,
permitting pressure under the piston to
escape quickly and the plunger member to 80
return to its normal position.

By the above described arrangement, I
provide an emergency governor testing ar-
rangement which is comparatively simple
in structure and reliable in operation, and 85
one which can be readily applied to exist-
ing types of emergency governors.

In accordance with the provisions of the
patent statutes, I have described the prin-
ciple of operation of my invention, 90
together with the apparatus which I now con-
sider to represent the best embodiment there-
of, but I desire to have it understood that the
apparatus shown is only illustrative and that
the invention may be carried out by other 95
means.

What I claim as new and desire to secure
by Letters Patent of the United States is:—

1. The combination with a shaft of an 100
elastic fluid turbine, of an emergency gov-
ernor comprising means carried by the shaft
which provides a recess extending trans-
versely of the shaft, a plunger in said re-
cess, said plunger having a portion which
105 fits the bore of the recess, and means for
supplying fluid under pressure to said recess,
while the shaft is rotating, comprising a
stationary wall which defines an annular
groove, a scoop carried by the shaft which
110 scoop moves in said groove as the shaft ro-
tates, a conduit which connects the scoop to
said recess, and means for supplying fluid
to said groove.

2. The combination with a shaft and an 115
emergency governor carried by it comprising
a plunger member, of means for apply-
ing fluid pressure to the plunger member
to effect movement of it, said means com-
prising a stationary wall adjacent the shaft,
120 said wall being provided with an annular
groove to which fluid is supplied, a scoop
carried by the shaft and adapted to pass
through said groove as the shaft rotates and
to take up fluid therefrom, and a conduit
125 for conveying said fluid from said scoop
to the plunger.

3. The combination with a shaft and an
emergency governor carried thereby com-
prising a radially movable member, of
means for applying fluid pressure to the 130

movable member to effect movement of it, said means comprising a scoop carried by the shaft and movable therewith in an annular path of movement, a conduit for conveying fluid from the scoop to the movable member, and means for supplying fluid to said scoop, throughout its annular path of movement.

4. The combination with a shaft and an emergency governor carried by it comprising a plunger member, of means for applying fluid pressure to the plunger member to effect movement of it, said means comprising a stationary wall adjacent the shaft, said wall being provided with an annular groove, a scoop carried by the shaft and adapted to pass through said groove as the shaft rotates, a conduit for conveying fluid from said scoop to the plunger, and means for supplying liquid to said groove in a direction opposite to that in which the shaft rotates, throughout the length of the groove.

5. The combination with a rotatable shaft and a fluid pressure actuated member carried thereby, of means for transmitting fluid pressure thereto while the shaft is rotating, said means comprising a fluid collecting

member carried by the shaft, which member moves in an annular path as the shaft rotates and in the same direction therewith, means for directing fluid into the path of said member and in an opposite direction to its movement therein, and a self-closing valve controlling the delivery of fluid to said directing means.

6. The combination with a rotatable shaft and a movable member carried thereby, of means for applying fluid pressure to said member to move it while the shaft is rotating, said means comprising a conduit means in the shaft for conveying fluid against the movable member, a fluid collecting member carried by the shaft, which member moves in an annular path as the shaft rotates and in the same direction therewith, means for directing a plurality of streams of fluid into the path of the collecting member in an opposite direction to that in which the member moves, and a self-closing valve controlling the fluid flow through said directing means.

In witness whereof I have hereunto set my hand this first day of October, 1925.

JAMES WILKINSON.
